DESIGN.

C. W. McCUTCHEON.
HEATING STOVE.

No. 18,616.

Patented Sept. 18, 1888.

UNITED STATES PATENT OFFICE.

CHARLES W. McCUTCHEON, OF PEEKSKILL, NEW YORK.

DESIGN FOR A HEATING-STOVE.

SPECIFICATION forming part of Design No. 18,616, dated September 18, 1888.

Application filed August 8, 1888. Serial No. 282,283. Term of patent 3½ years.

To all whom it may concern:

Be it known that I, CHARLES W. McCUTCHEON, a citizen of the United States, residing at Peekskill, in the county of Westchester and State of New York, have invented and produced a new and original Design for a Stove, of which the following is a specification, reference being had to the accompanying photograph, forming part thereof.

10 This photograph is a clear representation of my design, which consists of a cylinder, 1, beaded near the top and bottom, as at 15' and 16'. It rests upon an ash-box, 2, which is square at the top, its sides flaring outwardly 15 to the bottom 3. The several offsets made by the flaring enlargements are ornamented with rows of vertical fluting, as at *a a'*, the row *a* having a base line of scalloping, as at *b*. A plain surface, *c*, near the upper edge has also 20 a line of scalloping, *d*, as shown, at its base.

15 represents the door of the ash-box 2, and its lower part, *e*, is extended forward, so as to make the lowest part of the ash-box longer from the front to the rear than it is from side 25 to side. The bottom 3, with a plain drooping edge *f*, with a concaved upper corner, *g*, is likewise extended forward, giving a hearth-space, *h*. The door 15 has a line of vertical fluting, *i*, at its base. The curved extension *j* has a 30 scroll ornamentation, and above that is a register, 16, occupying most of the length of the door and having a continuation of the vertically-fluted line *a* at its sides, as at *k*. The top of the door bears a line of scalloping, *l*. Starting 35 from the base of the fluted line *a* and arching over the door is a band-like representation, *m*, projecting slightly beyond the top of the door when it is closed. A door-handle is shown at *4*.

40 The door to the ash-box is indicated by *3'*. An extension, *2'*, from the door has a projec-

tion sitting in a hole in the base 3. A small plate, *1'*, is secured to the base, and, resting upon the door-extension 2, keeps it in place when the door swings open.

45 The base is supported by legs 8, ornamented as shown.

The fire-door frame 9 has rosettes at the corners, surrounded by square frames, the frames being united by straight lines of molding, as 50 shown. At the top the molding forms an arch, with a number-plate in the center, and affords a name-space, *11*. The projecting sides taper toward the door and are fluted, as shown. The hinge-lugs 13 project boldly at the sides. The 55 door is formed with a double ovolو edge, and its ornamentation is made to correspond with that of the frame. Within the molded border a panel of mica, 12, is supported by a leafy scroll, *11*, as shown.

50 The top is round, and its plain drooping edge *n* is in keeping with that around the bottom. The vertical edge *o* is fluted to correspond with similar ornamentation on the base. The dome-like cover 5, surmounted by an urn, 6, containing a porcelain bowl, 7, is adapted to swing to one side and is not an integral part of the pins 5.

55 What I claim, and desire to secure by Letters Patent, is—

1. The design for a heating-stove herein shown and described, consisting of the base, cylinder, door, and frame, and top, of the shapes and ornamentation set forth.

2. In a design for a heating-stove herein shown and described, the base consisting of the ash-box and bottom, of the shape and ornamentation shown.

CHARLES W. McCUTCHEON.
